UNITED STATES PATENT OFFICE.

EDWARD HAGEN, OF PELICAN RAPIDS, MINNESOTA, ASSIGNOR OF ONE-HALF TO
ALVIN C. MELAND, OF PELICAN RAPIDS, MINNESOTA.

AUTOMOBILE RADIATOR.

Application filed May 1, 1925. Serial No. 27,197.

To all whom it may concern:

Be it known that I, EDWARD HAGEN, a citizen of the United States, residing at Pelican Rapids, in the county of Otter Tail 5 and State of Minnesota, have invented a new and useful Automobile Radiator, of which the following is a specification.

This invention relates to radiators, particularly the type commonly used on motor 10 vehicles, and its object is to provide means for equalizing the circulation of water therethrough, so as to cool the same most effectively in summer, and keep all parts of the radiator warm in winter to prevent it 15 from freezing.

The detailed construction of the invention and the principles of its operation will be fully explained in the following detailed description, which is to be read in connection 20 with the accompanying drawing illustrating the preferred embodiment thereof.

In the drawing:

Figure 1 is a front elevation of a radiator with the invention embodied therein, parts 25 thereof being broken away and shown in section.

Figure 2 is a vertical section taken on the line 2—2 of Figure 1.

The radiator to which the invention is 30 applied comprises a lower manifold or pan 5 connected by a series of small tubes 6 to an upper manifold 7. The upper manifold 7 has an inlet opening 10, through which the water circulates from a hose 11 35 leading from the water jacket of the engine. The lower manifold 5 has an outlet opening 8 from which the water returns through a hose 9 to the water jacket. The radiator has angle irons 12 secured thereto 40 by means of which it is attached to the automobile chassis, and the front side of the radiator is covered by a screen 13. The upper manifold 7 is provided with a filler neck 14, which is closed by a cap 15, and 45 the lower manifold 5 is provided with the usual drain cock 16.

In radiators as heretofore constructed, the greater part of the circulation takes place 50 through the tubes located immediately above the outlet opening 8, and in the summer the radiation is insufficient to properly cool the engine, while in extremely cold weather, owing to the very limited circulation through the tubes most remote from the outlet 55 8, the water therein is liable to become

frozen. In order to avoid such results, I have inserted in the lower manifold 5 a partition or baffle 17, preferably of copper or brass, which crosses the outlet opening 8 so as to cause the current passing 60 through the opening 8 to be drawn partly from each side of the partition, thereby causing a substantially equal volume of flow through the tubes at either side of the radiator. The major portion of this partition 65 plate 17 is substantially horizontal extending across the manifold 5. One end of the partition plate is curved downwardly, as at 18, and attached to the lower wall of the manifold 5 beneath the outlet 8, so that substantially 70 one-third of the opening is beneath the partition plate. The other end of the plate is curved upwardly, as at 19, and attached to the upper wall of the manifold 5 at a distance substantially two-thirds of the 75 width of the radiator from the side nearest the outlet opening. By this construction substantially one-third of the water discharged through the opening 8 is drawn 80 from the remote side of the radiator, after flowing downwardly through one-third of the tubes, which are located farthest from the outlet opening 8. Thus, a substantially equal flow is insured through the tubes at 85 either side of the radiator, and their temperature and radiation therefrom is equalized.

In the type of radiator shown herein, the continuous circulation of the water is generally insured by means of a rotary pump. 90 The invention, however, is not limited in its application to this particular type of radiator, but may be used to advantage in any type of radiator, whether the circulation is effected by a pump or by gravity. Modifications may also be made in the size, shape 95 and arrangement of the plate 17 without any material departure from the essential principles of the invention. It is my intention, therefore, to include all such variations 100 and modifications within the scope of what is claimed.

What is claimed is:

1. In an automobile radiator, the combination of a manifold having an outlet opening, a manifold having an inlet opening, a series of passageways connecting the two manifolds, and a partition plate extending across the outlet manifold in front of the outlet opening, so that a portion of the dis- 110

charge is drawn from each side of the partition plate, said partition plate being extended laterally so that one portion of the stream will be drawn from the remote side of the radiator.

- 5 2. In an automobile radiator, the combination of a lower manifold having an outlet opening, an upper manifold having an inlet opening, a series of passageways connecting 10 the two manifolds, and a partition in the lower manifold, the major portion of the partition being horizontal and joining the front and rear walls of the manifold, one end of the partition being curved upwardly 15 to meet the upper wall of the manifold and the other end crossing the outlet opening and terminating in a downwardly curved portion which meet the lower wall of the manifold.
- 20 3. In an automobile radiator, the combination of a manifold having an outlet opening near one end thereof, a manifold having an inlet opening, a series of passageways connecting the two manifolds, and a 25 partition joining the front and rear walls of the outlet manifold and extending across the outlet opening and causing the outlet stream to be drawn from opposite sides thereof, one end of the plate being curved to meet the wall of the manifold which is opposite to said passageways, 30 the other end of the plate being extended

toward the end of the manifold remote from the outlet and curved to meet the wall through which the passageways lead and dividing the same into the two sections which are substantially proportional to the respective portions of the outlet stream.

- 35 4. In an automobile radiator, the combination of a lower manifold having an outlet opening near one end thereof, an upper manifold having an inlet opening, a series of passageways connecting the two manifolds, and a partition plate joining the front and rear walls of the lower manifold and 40 extending across the outlet opening and dividing the outlet stream so that approximately one-third of the same comes from beneath the partition, said plate, as it crosses the outlet opening, being curved downwardly 45 to meet the lower wall of the manifold, the other end of the plate being extended toward the end of the manifold remote from the outlet and curved upwardly to meet the upper wall of the manifold at a point distant two-thirds of the length of the manifold from the outlet end, whereby to effect 50 an equalization of the flow through the tubes at either side of the radiator.

55 In testimony, that I claim the foregoing 60 as my own, I have hereto affixed my signature.

EDWARD HAGEN.
